UNITED STATES PATENT OFFICE.

JAMES M. WADSWORTH, OF FORT WORTH, TEXAS.

CARBON-REMOVING MECHANISM FOR STILLS.

Application filed December 27, 1921. Serial No. 525,171.

This invention relates to stills of the type that are used for cracking heavy petroleum hydrocarbons into lighter hydrocarbons such as gasoline.

- 5 In distilling heavy petroleum distillates by the so-called "cracking process" it is customary to subject the distillate to a temperature of approximately 800° F. under a pressure of about 100 lbs. per square inch
10 in an externally heated metal still so as to cause the heavy distillates to be cracked into lighter distillates which pass off as vapor that is subsequently condensed into gasoline. The residue of this operation is
15 a heavy fuel oil with a small percentage of free carbon, and if it is permitted to collect on the bottom of the still, the carbon forms into a cake of insulation between the liquid being distilled and the bottom of the still
20 that soon causes the steel bottom of the still to burn out,—often with very disastrous results. Various kinds of devices have been devised for scraping off and removing the carbon from the bottom of a pressure still
25 when the still is in operation, thus overcoming the necessity of shutting down the still at intervals and removing the carbon deposit from the bottom of the still, but said prior carbon scraping devices have not
30 proven entirely satisfactory, due, usually to the fact that they were so constructed and mounted in the still that unequal expansion and contraction between the still body and the scraping mechanism consisting of the
35 scraping devices and the actuating means for said devices, causes or tends to cause the scraping mechanism as an entirety to become inoperative.

The main object of my invention is to provide a still that is equipped with a practicable and highly efficient means for removing carbon from the bottom of the still when the still is in operation.

Another object is to provide a still that is equipped with a carbon scraping and removing apparatus of such construction that it will not be affected or rendered inoperative by unequal expansion and contraction between the still body and the parts which constitute said apparatus.

And still another object is to provide an oil still that is equipped with a carbon scraping and removing mechanism arranged inside of the still and constructed in the form of a unit that is not affected by longitudinal expansion and contraction of the

steel shell of the still and whose carbon scraping devices always remain in operative relationship with endless tracks over which they travel.

To this end I have devised a still that consists of a closed chamber, a movable means inside of said chamber operated from the exterior of the chamber for scraping off carbon or other residue from the bottom of the chamber and conveying it to a point of discharge and a supporting structure for said means combined with the still in such a manner that said carbon scraping and removing means as an entirety, will not be affected or rendered inoperative by unequal expansion and contraction between same and the steel shell of the distilling chamber. Preferably, the carbon scraping and removing means consists of one or more scraping devices, and an actuating means for said devices consisting of endless chains or other flexible or jointed elements that pass over rotatable driving devices arranged adjacent one end of the still and over idlers arranged adjacent the opposite end of the still. The supporting structure previously referred to is arranged inside of the still in such a manner that the steel shell of the still can expand and contract without exerting any strains or having any effect whatsoever on the flexible elements that operate the scraping devices or on the idlers over which said flexible elements travel. The particular design of said supporting structure is immaterial, but it is preferably provided with parts that act as guides or tracks on which the scraping devices travel.

Figure 1 of the drawings is a horizontal longitudinal sectional view of a still equipped with a carbon scraping and removing mechanism constructed in accordance with my invention.

Figure 2 is a vertical longitudinal sectional view of said still.

Figure 3 is a transverse sectional view of the still; and

Figure 4 is a transverse sectional view similar to Figure 3, illustrating a slight modification of the invention.

Referring to the drawings which illustrate the preferred form of my invention, A designates a still having a discharge opening 1 formed in its bottom adjacent one end of the still through which carbon is discharged from the still by one or more carbon scraping devices that travel longitudi-

nally of the still and scrape off carbon that becomes deposited on the bottom of the still. The carbon scraping devices just referred to may either consist of one or more gangs of 5 weighted knives or scraping devices B, as shown in Figures 1, 2 and 3, or one or more chains B', as shown in Figure 4. Said scraping devices are moved longitudinally of the still by a mechanism operated from the 10 exterior of the still and consisting preferably of a horizontally-disposed drive shaft C arranged adjacent one end of the still and provided with sprocket wheels 2, a pair of endless sprocket chains or other flexible or jointed elements D that extend around the sprocket wheels 2, and a pair of idlers 3 arranged adjacent the opposite end of the still over which the chains D travel. Each 15 scraping device, or rather, each gang of scraping devices, is supported by a transversely-disposed member E hereinafter referred to as the scraping device carrier that is connected with the chains D in such a way that it will move longitudinally of the 20 still towards the right, looking at Figure 2, thereby causing the scraping devices B or B' to dislodge the carbon on the bottom of the still and move said carbon towards the discharge opening 1 in the bottom of the still 25 and will then travel upwardly over the sprockets 2 and move longitudinally of the still in the opposite direction when the chains D are in operation.

The drive shaft C is supported at one end 30 by a bearing 4 arranged on the inside of the still and the opposite end of said shaft projects outwardly through a stuffing box or packed bearing 5 in the side wall of the still, as shown in Figures 1 and 3. The idlers 3 at 35 the opposite end of the still are connected to a horizontally-disposed shaft 6, but instead of mounting the shaft 6 in the side walls of the still, as has heretofore been the practice in stills equipped with carbon scraping devices operated by endless chains, I mount the idler shaft 6 on a supporting structure 40 separate and distinct from the shell of the still A and which is arranged inside of the still in such a manner that it will not be affected by the longitudinal expansion and contraction of the shell of the still. Said supporting structure is also utilized to sustain parts that maintain the scraping devices 45 in a certain position with relation to the bottom of the still, and in the preferred form of my invention, as herein illustrated, said supporting structure is combined with endless tracks F that are engaged by rollers or other suitable guiding devices 7 on the scraping device carriers E, as shown in Figures 3 and 4. The supporting structure just referred to can be formed conveniently from commercially rolled bars or structural shapes such as angle bars, I-beams, channels or the 55 like connected together in such a way as to

produce a skeleton-like frame that is arranged longitudinally of the still A intermediate the top and bottom of the still, as shown in Figure 2. In the accompanying drawings I have designated said supporting structure or frame by the reference character G, it being understood that the particular construction or design of said frame is immaterial, so far as my invention is concerned. The endless tracks F are rigidly connected 70 to the frame or supporting structure G, and said frame is provided at one end with vertically-disposed plates or webs 8 equipped with bearings 8^a through which the drive shaft C passes, said bearings 8^a co-operating 75 with the shaft bearings 4 and 5 on the shell of the still in such a way as to insure the end portion of the supporting structure G through which the drive shaft passes remaining in proper spaced relation with the 80 shell of the still. At the opposite end of said frame are vertically-disposed plates or webs 9 equipped with bearings 9^a through which the idler shaft 6 passes. The frame G is suspended within the still A in such 85 a manner that it is free to expand and contract longitudinally relatively to the steel shell of the still, thereby eliminating the possibility of the scraping devices or the operating mechanism of the scraping devices being affected or rendered inoperative by unequal expansion and contraction between the steel shell of the still and the parts 90 of the scraping mechanism. One convenient way of sustaining the supporting structure 100 for the operating mechanism of the scraping devices inside of the still is to provide the still with transversely-disposed stationary supports 10 on which the frame G rests freely, said supports 10 consisting of I-beams 105 or other commercially rolled shapes arranged adjacent the ends of the still, as shown in Figure 1. When the still is in operation the shell of the still expands and contracts a greater degree than the parts arranged inside of said shell, but this has no injurious effect on the parts constituting the carbon scraping and removing mechanism, due to the fact that the frame G is practically 110 floatingly mounted inside of the shell of 115 the still. In other words, the frame G may be said to be rockably mounted at one end on the drive shaft C and supported at its opposite end by a stationary part 10 on which it is free to slide back and forth as said 120 frame G expands, the left hand end portion of said frame which carries the idler shaft 6 also being capable of expanding and contracting laterally relatively to the shell of the still without producing any injurious 125 results.

In a still of the construction above described the scraping devices and the operating mechanism for same constitute a unit 130 separate and distinct from the shell of the

still that is capable of expanding and contracting without producing any unequal strains on the parts of said mechanism or on the shell of the still. Moreover, as the 5 scraping device carriers E travel on continuous tracks F, there is little liability of the scraping devices failing to operate properly and travel in a definite path first longitudinally over the bottom of the still towards the 10 discharge opening 1 and then longitudinally of the still in the opposite direction preparatory to the next scraping operation.

A still of the construction above described is inexpensive to build and is easy to maintain 15 in operative condition, due, of course to the fact that the carbon scraping apparatus is constructed in the form of a single unit separate and distinct from the shell of the still that is practically floatingly mounted 20 inside of the still.

Having thus described my invention, what I claim as new and desire to secure by Letters Patent is:

1. A still provided with an elongated 25 shell, a supporting structure in said shell arranged with one of its end portions in substantially fixed relation with the shell and its opposite end portion free to expand 30 and contract longitudinally relatively to the shell, a rotatable device carried by the shell and arranged adjacent the fixed end of said supporting structure, a rotatable device mounted on said supporting structure adjacent 35 the free end of same, an endless flexible element that travels over said rotatable devices, and a scraping device actuated by said flexible element for removing sediment from the bottom of the shell.

40 2. A still, comprising a shell provided adjacent one end with an outlet through which sediment can be removed, a scraping device arranged inside of said shell for removing sediment from the bottom of same 45 and discharging the sediment through said outlet, an endless flexible element in said shell for actuating said scraping device, a supporting structure in said shell arranged longitudinally of same with one of its end 50 portions in substantially fixed relation with the shell and its opposite end portion free to move longitudinally and also laterally with relation to the shell, and rotatable elements arranged adjacent the opposite ends

of said supporting structure around which 55 said flexible element travels.

3. A still, comprising a shell provided adjacent one end with an outlet through which sediment can be removed, a scraping device arranged inside of said shell for removing sediment from the bottom of same and discharging the sediment through said outlet, an endless flexible element in said shell for actuating said scraping device, a supporting structure in said shell arranged 60 longitudinally of same with one of its end portions in substantially fixed relation with the shell and its opposite end portion free to move longitudinally and also laterally with relation to the shell, rotatable elements 65 arranged adjacent the opposite ends of said supporting structure around which said flexible element travels, and an endless track on said supporting structure that determines the path of travel of said scraping device. 75

4. In a still, a drive shaft arranged transversely at one end of the still and operable from the exterior of the still, a sprocket wheel on said shaft, an idler sprocket wheel arranged adjacent the opposite end of the 80 still, a shaft on which said idler is mounted, a chain that travels around said sprockets, a scraping device actuated by said chain, and a supporting structure floatingly mounted in said still that carries said idler shaft and 85 provided with an endless track on which said scraping device travels.

5. A still, comprising a shell provided adjacent one end with an outlet through which sediment can be removed from the 90 still, a scraping device arranged inside of the still and adapted to be moved longitudinally of same for removing sediment from the bottom of the still and discharging it through said outlet, a carrier for said scraping device arranged transversely of the still, endless chains for actuating said carrier, an idler shaft provided with sprockets around which said chains travel, a supporting frame for said idler shaft arranged inside of the 95 still shell and capable of moving independently of the still shell longitudinally and laterally, and continuous tracks on said frame on which the scraping device carrier travels. 100
